tion of Illinois

Application February 28, 1945, Serial No. 580,181

8 Claims. (Cl. 169—11)

1

This invention relates to new and useful improvements in methods of and apparatus for discharging fire extinguishing mediums and for extinguishing fires.

The copending application, Serial No. 551,869, filed by Charles A. Getz, on August 30, 1944, among other things, discloses and broadly claims a method of and apparatus for discharging carbon dioxide and foam, either individually or in combination, to effect the extinguishment of certain "classes" of fires. For example, "class B" fires can be extinguished more quickly and effectively with an initial, brief application of carbon dioxide and foam and a final, prolonged application of foam by itself than with either carbon dioxide or foam when used alone, or with any other known extinguishing mediums when used alone or in any desired combination.

The aforesaid application specifically discloses mechanical air foam as one of the foams that is used with carbon dioxide to effect the extinguishment of fires. Mechanical air foam is produced by flowing under pressure a mixture of water and a foam stabilizing agent in such a manner that air from the surrounding atmosphere will be drawn into the flowing mixture and entrapped in the stable bubbles of the resultant foam.

As all foams are broken down by flame or intense heat, it will be appreciated that when mechanical air foam is applied directly to flame or to intensely heated surfaces in a fire zone, before the water portion of the foam has had an opportunity to cool down these surfaces, the mechanical air foam bubbles will be broken down and the air entrapped therein will be liberated, with the result that combustion supporting oxygen is delivered to the fire. This is one of the principal differences between mechanical air foam and chemical foam; i. e., the bubbles of chemical foam are filled with carbon dioxide vapor which is liberated when the bubbles are broken down and has a smothering effect which aids in extinguishing a fire.

Attempts have been made in the past to produce mechanical foam which will not release oxygen to the fire by substituting an inert gas for the air that is drawn into the flowing mixture of water and stabilizing agent. These prior attempts have not proved satisfactory, or commercially practical, for the following reasons:

1. A proper supply of compressed inert gas had to be maintained in readiness for use at all times and the gas had to be piped to the point of delivery to the flowing mixture.

2

2. Foam bubbles formed with compressed inert gas entrapped therein were found to be less stable or durable than foam bubbles containing air at atmospheric pressure because the internal pressure exerted by the compressed inert gas caused the bubbles to break down more readily.

3. Although it is entirely satisfactory to use air, instead of inert gas, after a fire is subdued to the point where there no longer remains sufficient flame or intense heat to break down to a substantial extent the foam bubble formation, thereby effecting a reduction in the amount of inert gas required, this saving could not be realized in connection with these prior attempts without the addition of a suitable switching valve in the supply pipe for the inert gas.

Because of the above noted objections, the manufacturers of mechanical foam producing equipment of today provide for the use of air as the bubble entrapped medium, and depend on a prolonged, high rate of discharge for eventually effecting the desired extinguishment.

It is the primary object of this invention to provide a method of and apparatus for producing a fire extinguishing discharge which consists of carbon dioxide and mechanical foam with the bubbles of the foam having entrapped therein carbon dioxide that is obtained from the carbon dioxide portion of the discharge.

30 A further primary object of the invention is to provide a method of and an apparatus for producing a fire extinguishing discharge which consists of carbon dioxide that has its snow and vapor components separated and mechanical air foam with the foam bubbles having entrapped therein carbon dioxide vapor that is obtained from the separated vapor component of the carbon dioxide discharge.

40 A still further important object of the invention is the provision of a method of and apparatus for extinguishing a fire by applying thereto a combined discharge of carbon dioxide and mechanical foam, with the bubbles of the foam having entrapped therein carbon dioxide obtained from the carbon dioxide portion of the discharge, until the flame and temperature conditions in the fire zone are such that the foam bubbles will not be materially affected thereby, and then applying to the fire a discharge of mechanical air foam alone, with the bubbles of the foam having entrapped therein air obtained from the surrounding atmosphere.

Another object of the invention is to provide a fire extinguishing method and apparatus for producing a discharge of carbon dioxide and mechan-

ical foam, with the snow and vapor components of the carbon dioxide separated and arranged so that the vapor component shields the snow component from the surrounding atmosphere and with the mechanical foam being formed from water, a stabilizing agent, and vapor obtained from the shielding vapor component of the carbon dioxide portion of the discharge.

Still another object of the invention is to provide fire extinguishing apparatus which is operable to effect discharge of carbon dioxide alone, mechanical air foam alone, or a combination of carbon dioxide and mechanical foam which has carbon dioxide vapor entrapped in the foam bubbles.

A further object of the invention is to provide apparatus for producing a fire extinguishing discharge that consists of a dense carbon dioxide snow core, a carbon dioxide vapor envelope surrounding and shielding the snow core, and one or more streams of mechanical foam, having carbon dioxide vapor obtained from the aforesaid vapor envelope entrapped in its bubbles, arranged adjacent the margin of the carbon dioxide vapor envelope.

Other objects and advantages of the invention will be apparent during the course of the following description.

In the accompanying drawings, forming a part of this specification and in which like numerals are employed to designate like parts throughout the same,

Figure 1 is a front elevational view of one form of fire extinguishing apparatus embodying this invention,

Figure 2 is a central vertical sectional view taken on line 2—2 of Fig. 1,

Figure 3 is a front elevational view of a modified form of fire extinguishing apparatus embodying this invention;

Figure 4 is a top plan view of the apparatus shown in Fig. 3,

Figure 5 is a vertical sectional view taken on line 5—5 of Fig. 3, and

Figure 6 is a horizontal sectional view taken on line 6—6 of Fig. 5.

In the drawings, wherein for the purpose of illustration are shown the preferred embodiments of this invention, and first particularly referring to Figs. 1 and 2, the reference character A designates in its entirety the carbon dioxide discharge portion while the reference character B designates each one of the two foam generating and discharging portions of the complete fire extinguishing apparatus embodying this invention. The carbon dioxide discharge portion A of this apparatus will be described first.

The carbon dioxide discharge portion or nozzle A is supplied with liquid carbon dioxide by means of the pipe line 10 which may extend to any suitable source of supply, such as a bank of high pressure cylinders or an insulated and automatically refrigerated storage tank. It is preferred, however, to obtain the liquid carbon dioxide from the insulated and refrigerated tank so that the liquid carbon dioxide can be delivered to the discharge nozzle A at a predetermined, constant subatmospheric temperature, and its corresponding low vapor pressure because of the higher percentage of snow yield that would be obtained.

Any suitable control valve, not shown, should be provided in the pipe line 10 for starting and stopping the flow of liquid carbon dioxide through the latter. The pipe line 10 may be of a rigid character if the apparatus of Figs. 1 and 2 is

employed as a part of a fixed fire extinguishing system, or if the apparatus is associated with mobile fire fighting units of the type disclosed in the Eric Geertz patent, No. 2,352,379, issued June 27, 1944. This pipe line 10, also, may take the form of a flexible hose line if desired. If a flexible hose line is employed, several feet of the pipe line 10 located immediately adjacent the discharge nozzle A will take the form of a more rigid handle or "playpipe" to facilitate manual handling of the apparatus.

The carbon dioxide discharge nozzle A is of the type disclosed and broadly claimed in the patent to Hilding V. Williamson, No. 2,357,039, issued August 29, 1944. The liquid carbon dioxide supply pipe line 10 is suitably threadedly connected to the stem or shank 11 of the nozzle A. This stem or shank 11 is provided with a bore 12 for delivering the liquid carbon dioxide to the interior of the body portion of the nozzle. The outer or forward end 13 of this bore communicates with the interior of a deflector element and cooperates with this element to form a flow path for the liquid carbon dioxide. The stem or shank 11 has formed on its outer end a radially extending flange 14 formed with a circular series of orifices 15 through which the liquid carbon dioxide is released to permit sudden expansion so that its pressure will drop below 75 pounds per square inch, absolute, which will cause a certain percentage of the liquid to flash to snow while the remainder of the liquid is vaporized. This annular flange 14 is provided with a circular series of threaded openings 16, for a purpose to be explained at a later point. Externally, the stem or shank 11 is provided with a rearwardly curved or flared surface 17 that terminates in a shoulder 18.

The deflector element referred to above is identified by the reference character 19 in Figs. 1 and 2. This deflector element is secured to the flange 14 by means of the series of screws 20 that are threaded into the holes 16 of the flange 14. The deflector is partially hollowed out so as to control the direction of flow of the liquid carbon dioxide to the discharge orifices 15. For that reason, the interior of the deflector is provided with a conically shaped projection 21 that is axially aligned with the bore 12 of the shank or stem 11. The interior of the deflector element 19, radially outwardly of the spreading projection 21, is provided with the curved surfaces 22 that function to change the direction of flow of the liquid carbon dioxide so that it will be directed rearwardly through the discharge orifices 15. The inner or rear portion of the deflector element 19 is belled or curved outwardly at 23 to form an internal curved surface 24 that lies opposite to and cooperates with the curved exterior surface 17 of the stem or shank 11. Fig. 2 clearly shows that these two cooperating surfaces 17 and 24 diverge with respect to each other in any radial section to form an annular passageway that gradually increases in depth or thickness. This increase functions to permit further expansion of the released carbon dioxide so that the pressure of the same will drop still further and will provide for flashing of whatever liquid may remain as a part of the flowing material. The outer portion of the deflector element 19 is illustrated in Figs. 1 and 2 as being formed with radial ribs 25 which form the valleys 26 that are partially longitudinally curved so as to deflect forwardly or axially

any of the discharged medium that comes in contact with the same.

The deflector element 19, and the cooperating portion 17 of the stem or shank 11, are enclosed within a chambered body or casing which is formed by the inner portion 27 and the outer portion 28. The inner portion 27 of the body or casing is dish-shaped and is centrally cut away at 29 to permit the inner portion of the stem or shank 11 to pass therethrough so that the shoulder 18 will act as a seat or an abutment for this inner portion 27 of the body or casing. Any suitable means may be provided for securing the body or casing portion 27 to the shoulder portion 18, such as by welding or by the use of suitable screws or both. The outer portion 28 of the body or casing is of cylindrical shape and has its inner edge portion overlapping or telescopically associated with the outer marginal edge portion of the inner body part 27 to provide a lapped joint 30. Rivets, welding, or the like, may be employed for rendering this joint permanent. Figs. 1 and 2 clearly show that the body or casing of the carbon dioxide discharge nozzle cooperates with the stem or shank 11 to provide a closed rear wall while leaving the front of the apparatus entirely open. The body or casing additionally cooperates with the stem or shank 11 and the deflector element 19 to form an annular chamber for receiving the circular series of flow controlling and directing units 31.

These units 31 are equally spaced around and extend radially of the stem or shank 11 and the deflector element 19. Each one of these units include a semi-circular or semi-cylindrical band 32 which is flanged at both of its longitudinal edges 33, see Fig. 2. The inner transverse edge 34 of each one of these bands 32 is suitably anchored in close proximity to or in contact with the periphery of the flared portion or surface 17 of the stem or shank 11. The outer edge 35 of each one of these bands 32 terminates in the plane of the outer face of the body or casing portion 28 and the outer edges of the deflector element ribs 25.

The opposite sides of each one of these flow controlling and directing units 31 are formed by wall members 36 which lie inside of the edge flanges 33 and are suitably secured thereto. Figs. 1 and 2 show the opposite side walls of each adjacent pair of units 31 as being formed by a single piece of sheet material with the center or intermediate portion of each one of these side wall forming pieces designated by the reference character 37. These center or intermediate portions 37 function to bridge the gaps or spaces between the inner edges or sides of adjacent units 31.

Fig. 2 clearly discloses the side walls 36 of the several units 31 as having apertures 38 formed therein. These apertures are located in the outer or front halves of the side walls 36; i. e., relatively close to the outer edges 35 of the bands 32. Each flow controlling and deflecting unit 31 has mounted within the same a plow-shaped deflecting and separating element 39. These elements are of V- or wedge-shape in section with mounting flanges 40 formed on the sides thereof for securing, such as by welding, the elements 39 in their proper places within the units 31. Fig. 2 discloses these deflecting and separating elements 39 as being arranged with respect to the side wall openings or apertures 38 so that the lateral sloping surfaces 41 of each element 39

will split or spread any material flowing through the interior of a unit 31 so that this material will be deflected through the cooperating side wall openings or apertures 38. These elements 39 are shown in Fig. 2 as being arranged so that their outer transverse edges 42 are spaced from the inner surfaces of the outer end portions of their associated bands 32. In other words, a space or gap is left between the inner surface of the band 32 of each one of the units 31 and the outer edge 42 of its associated deflecting and separating element 39 through which the extinguishing medium may flow to the outer edge 35 of the band 32.

The mode of operation of this carbon dioxide discharge nozzle is explained in detail in the aforesaid Hilding V. Williamson patent and for that reason its mode of operation will be only generally set forth herein. Liquid carbon dioxide, of any desired pressure and temperature, will be delivered to the bore of the shank or stem 11 and will flow as a liquid to the discharge orifices 15. As the liquid carbon dioxide leaves these orifices, it expands suddenly and its pressure drops to such an extent that the liquid flashes and vaporizes. The carbon dioxide that enters the space formed between the outwardly flowing surfaces 17 and 24, therefore, takes the form of a mixture of snow and vapor. Depending upon the temperature of the liquid carbon dioxide that is delivered to this discharge nozzle, a certain percentage of the same will flash into snow as a result of the self-cooling action that is produced. In other words, the entire discharge from the peripheral mouth, formed by the outer edges of the surfaces 17 and 24, will consist of a mixture of snow and vapor.

This snow and vapor mixture, as it leaves the aforesaid peripheral mouth, will be flowing in a truly radial direction. Some portions of the mixture will pass directly into the various flow controlling and directing units 31. The remainder of the mixture will be split and deflected laterally in opposite directions by the axially extending portions 37 of the side wall forming pieces 36. These deflected portions of the mixture, therefore, will be directed into the several units 31.

The curved bands 32 of the flow controlling and directing units 31 will deflect the flowing mixture from its straight line, radial path and convert this straight line flow into a curvilinear flow or motion. As the carbon dioxide snow of the mixture is many times more dense than the carbon dioxide vapor, and as the velocity of both of these components is the same, the snow offers more resistance to the deflecting force exerted by the obstructing, curved bands 32 with the result that the snow will move to the outer side of each one of these curvilinear flow paths for the material. The snow, in seeking this outer portion of each flow path, will crowd or force the vapor inwardly away from the inner surfaces of the various bands 32. The difference in density of the snow, as compared to the vapor, therefore, effects a segregation of these two components. The snow is segregated at or close to the outer side of each one of the curvilinear flow paths while the vapor is segregated on the inner side of each path.

As the segregated snow and vapor reach the outer side of each one of the flow controlling and directing units 31, the snow passes through the gap or space left between the inner surface of its band 32 and the outer edge of this flow splitting and separating element 39. The inwardly

positioned, segregated vapor, however, strikes the sloping surfaces 41 of the various elements 39 and is directed laterally through the side wall apertures 38 into the portions of the body or casing which lie between adjacent units 31. The segregated and separated snow passes radially outwardly beyond the edges 35 of the several bands 32 and is directed into the valleys 26 of the deflector element 19. The curved inner surfaces of these valleys deflect the snow so that it will flow, or will be discharged, to the atmosphere in an axial direction with respect to the entire carbon dioxide discharge nozzle. This discharge of all of the separated snow from all of the units 31 causes the snow to be assembled into a compact, dense core. The separated vapor will leave the spaces between the adjacent units 31 and will flow in an axial direction relative to the discharge nozzle. The vapor is in this way discharged radially outwardly of the dense snow core. Because the areas of discharge for the vapor are spaced from each other by distances that equal the width of the flow controlling and directing units 31, the vapor discharges will be separated from each other immediately adjacent the front face of the carbon dioxide discharge nozzle. However, the various vapor discharges will blend together a short distance in advance of the nozzle and will form a surrounding or enclosing vapor envelope for the compact, dense snow which forms the core of the composite discharge of carbon dioxide.

From this description of the mode of operation of the discharge nozzle for the carbon dioxide, it will be appreciated that there is provided a discharge stream which is of substantially circular or cylindrical shape in transverse section. In Fig. 2 of the drawings, the dotted lines D are intended to represent the peripheral margin of the compact, dense snow core. All of the carbon dioxide that is discharged radially outwardly of these lines D, therefore, will be the separated carbon dioxide vapor that forms the snow shielding envelope.

The foam generating and discharging portions B of the fire extinguishing apparatus disclosed in Figs. 1 and 2 now will be described in detail.

It will be noted from the two figures of the drawings that the two foam generating or discharge portions, or guns, B are located on diametrically opposite sides of the carbon dioxide discharge nozzle A and that these foam guns are structurally or operatively associated with a substantial portion of the periphery of the carbon dioxide nozzle. It will be appreciated that the size of the various elements that constitute each one of these foam guns will determine to a considerable extent the volume or quantity of foam that is generated and discharged. Therefore, if a greater total volume of foam is desired for certain extinguishment work, three or more foam guns B can be provided and distributed or spaced equal distances from each other around the periphery of the carbon dioxide discharge nozzle A. Additionally, if a lesser amount of foam is desired, one of the two foam guns B, illustrated in Figs. 1 and 2, can be dispensed with.

Each one of these foam guns is illustrated as having a pipe line 45 which is employed for supplying a suitable mixture of water and any desired, commercial foam stabilizing agent. This mixture, also, can include a suitable anti-freeze material or chemical when the fire extinguishing apparatus is used under ambient temperature conditions that would cause the water to freeze.

The water and stabilizing agent mixture can be supplied from any suitable source and is intended to flow through the pipe lines 45 under any desired pressure. It will be noted that these pipe lines are intended to extend longitudinally of and to be grouped with or attached to the carbon dioxide supply pipe line 10. Additionally, these foam mixture pipe lines 45 curve around or radially and axially of the periphery of the carbon dioxide discharge nozzle A. These pipe lines 45, therefore, will be flexible or rigid depending upon the character of the pipe line 10 and the use to which the fire extinguishing apparatus is applied; i. e., incorporated in a fixed fire extinguishing system or used as a discharge device for a hose line.

Each one of the pipe lines 45 extends to and is suitably connected with a coupling or discharge manifold 46. This coupling or manifold is hollowed out and is provided with a suitable number of orifice tips 47 mounted in its front wall 48 and adapted to discharge the water and stabilizing agent mixture or solution from the coupling or manifold. A suitable strainer element 49 is mounted in the element 46 and functions to separate out foreign matter and solid particles that might clog the tips 47.

Suitably attached to the discharge end of the coupling or discharge manifold 46 is a hollow member 50 that functions to provide a foam generating chamber 51 and a pick-up spout 52. This pick-up spout portion 52 of the member 50 is illustrated in Figs. 1 and 2 as extending to the annular space formed within the outer portion 28 of the body or casing and the peripheries of the associated flow controlling and directing units 31. That is to say, the outer halves of these units 31 curve radially inwardly away from the body or casing portion 28 to provide space for the inlet throat 53 of the pick-up spout 52.

Fig. 1 shows this inlet throat 53 of each pick-up spout 52 as being aligned with three of the carbon dioxide vapor discharge spaces that are left between the flow controlling and directing units 31. Therefore, when carbon dioxide vapor is being discharged by the carbon dioxide nozzle A, some of this vapor will enter each one of the two pick-up spouts 52 and this vapor will be delivered to the foam generating chambers 51.

The bringing together of the carbon dioxide vapor and the mixture or solution of water and foam stabilizing agent in the chambers 51 causes foam to be produced. This foam has the carbon dioxide vapor entrapped in its bubbles. The foam generated in each chamber 51 is discharged through the associated foam delivering and directing tube 54.

These delivering and directing tubes 54 are illustrated in Figs. 1 and 2 as having their axes 60 arranged in parallelism with the axis of the carbon dioxide discharge nozzle A. It will be appreciated, however, that these foam tubes 54 may be positioned so that their axes will form either acute or obtuse angles with respect to the axis of the carbon dioxide discharge nozzle A. If the axes of the foam directing tubes 54 are arranged at acute angles with respect to the axis of the carbon dioxide discharge nozzle A, the resultant foam streams will be directed into 70 the carbon dioxide stream for being blended with or entrained by the carbon dioxide. If the axes of the foam directing tubes 54 form obtuse angles with respect to the axis of the carbon dioxide discharge nozzle A, the foam streams will 75 be caused to diverge or spread out relative to the

carbon dioxide stream. The character of the hazards to be protected and the types of fires that will be produced by different hazards will determine the angular relationship that should be provided between the axes of the foam delivering and directing tubes 54 and the axis of the carbon dioxide discharge nozzle A.

It will be appreciated that suitable control valves will be provided in the supply pipe lines 45 for the foam guns B. By means of these control valves, which are not shown, and the control valve, not shown, for the carbon dioxide supply pipe line 10, the illustrated fire extinguishing apparatus may be used or operated for producing a combined discharge of carbon dioxide and foam by opening all of said valves. If it is desired to discharge only carbon dioxide, the control valves for the supply pipe lines 45 will be closed. If it is desired to discharge only foam, the control valves for the pipe lines 45 will be opened and the control valve for the carbon dioxide supply line 10 will be closed. As no carbon dioxide vapor will be discharged by the nozzle A under this last mentioned operating condition, the pick-up spouts 52 will not receive any carbon dioxide vapor. However, the aspirating action produced by the discharge of water and a foam stabilizing agent from the orifice tips 47 through the generating chamber 51 and into the aligned foam delivering and directing tube 54 will cause air from the surrounding atmosphere to be drawn into each pick-up spout 52 through its inlet throat 53. This atmospheric air will be delivered to the foam generating chambers 51 and will be entrapped in the bubbles of the foam produced in these chambers.

Figs. 3 to 6 inclusive disclose a modified form of fire fighting apparatus which is designed for producing a combined discharge of carbon dioxide and foam or discharges of carbon dioxide by itself and discharges of foam by itself. The difference between the discharges produced by the apparatus of Figs. 3 to 6 inclusive and the apparatus of Figs. 1 and 2 relates primarily to the cross sectional shape of the discharge streams. With the apparatus of Figs. 1 and 2, the carbon dioxide stream and the foam streams are each of circular cross section. With the apparatus of Figs. 3 to 6 inclusive, the single carbon dioxide stream and each one of the several foam streams is of elongated shape in cross section, or with each stream having a major and a minor cross sectional dimension. The type of discharge provided by the apparatus of Figs. 3 to 6 inclusive is best suited for extinguishing ground fires or for applying the extinguishing medium over a large surface area of a pool or confined body of flammable fluid. Due to the large surface coverage provided by the apparatus of Figs. 3 to 6 inclusive, this apparatus can be installed in a fixed position with respect to the hazard or it can be mounted on the front of a mobile fire fighting unit.

The fire extinguishing apparatus of Figs. 3 to 6 inclusive consists of a carbon dioxide discharge nozzle which is designated in its entirety by the reference character G and a plurality of foam generating and discharging nozzles or guns H.

Figs. 3 to 5 inclusive illustrate the relative arrangement of the foam guns H with respect to the carbon dioxide nozzle G. As illustrated, two of the foam guns are associated with the upper longitudinal margin of the carbon dioxide nozzle while two additional foam guns are associated with the lower longitudinal margin of the

carbon dioxide nozzle. Each one of these longitudinally aligned pairs of foam guns extends throughout a major portion of the length of the carbon dioxide nozzle. It will be appreciated that the combined length of each aligned pair of foam guns may be increased or decreased as desired to vary the volume of foam that is generated with reference to the volume of carbon dioxide that is discharged by the nozzle G. Additionally, either the upper or the lower pair of foam guns may be dispensed with if only one pair of foam guns is required, or will produce a sufficient quantity of foam for a given type of hazard. Under certain operating conditions, it may be necessary to employ only one of these foam guns H in combination with the carbon dioxide discharge nozzle G. When only one foam gun is employed, it, preferably, will be centrally located with respect to the length of the carbon dioxide nozzle G and it may be associated with either the top or the bottom longitudinal margin of the carbon dioxide nozzle.

The carbon dioxide nozzle portion of this fire extinguishing apparatus is best illustrated in Figs. 3 to 5 inclusive and the detail structural features will be described in connection with these figures.

This carbon dioxide nozzle G is of the same general construction as that disclosed in the Hilding V. Williamson Patent No. 2,357,040, issued August 29, 1944. This nozzle includes a supply pipe line 55 which is employed for delivering liquid carbon dioxide to the nozzle. This pipe line may receive its liquid carbon dioxide from either a bank or high pressure cylinders, or from a single insulated and automatically refrigerated storage tank in the same manner as has been described in connection with the carbon dioxide nozzle A of Figs. 1 and 2. The forward end of the pipe line 55 is connected to the right angularly arranged branches 56 and 57. These branches extend in opposite directions and are suitably connected to the intermediate portions of discharge pipes 58 and 59 respectively. The pipes 58 and 59 are illustrated in Figs. 3 and 5 as being arranged in parallelism with respect to each other. These discharge pipes are suitably closed at their opposite outer ends and each pipe is provided with a longitudinally arranged series of discharge apertures or orifices 60. Fig. 5 discloses these orifices or apertures as facing in a generally rearward direction, rather than a forward direction, and it is to be understood that the apertures or orifices may be spaced at any desired or suitable distance from each other.

Each one of these apertured discharge pipes 58 and 59 is arranged within a merging and segregating chamber 61. These chambers are arranged in parallelism with each other and each one is provided with a curved rear wall 62 that is joined to the side, parallel walls 63. Each one of these chambers 61 is entirely open at its front, or at the portion opposite its curved rear wall 62, and both ends of these chambers are closed by the end walls 64.

Fig. 5 discloses the discharge pipes 58 and 59 as being welded at 64 to the outer side walls 63 of their respective chambers 61. The remaining, or inner, side walls 63 of the parallel chambers bear against each other and they may be welded, or otherwise suitably connected, as at 65. A reinforcing or bracing plate 66 is disclosed in Fig. 5 as being welded, or otherwise suitably connected, 75 to the outer surfaces of the curved inner walls

11

62 of the chambers for further interconnecting these two chambers.

By inspecting Fig. 5, it will be seen that the longitudinal series of discharge orifices or apertures 60 of each discharge pipe 58 or 59 point or face in the general direction of the zone or region where its associated rear, curved chamber wall 62 merges with the outer side chamber wall 63. The importance of this direction of discharge will be apparent as the description proceeds.

The mode of operation of this carbon dioxide discharge nozzle now will be described. Liquid carbon dioxide of any desired temperature, and corresponding vapor pressure, will flow under its own vapor pressure through the pipe line 55 and the branch lines 56 and 57 to the parallel discharge pipes 58 and 59 respectively. The liquid carbon dioxide in these discharge pipes will be released to the interiors of the chambers 61 through the constricted orifices or apertures 60. Due to the sudden drop in pressure which occurs as a result of releasing the liquid carbon dioxide in this manner, the liquid is converted to a mixture of snow particles and vapor. Each aperture or orifice 60 will provide a separate jet or stream of this carbon dioxide mixture. These jets or streams will partake of straight-line motion until their paths are obstructed by the inner surfaces of the chamber walls. The curved formation of each chamber rear wall 62 will cause the flowing mixtures of carbon dioxide snow and vapor to be deflected so that the said normal straight-line motion will be converted to a curvilinear motion. In addition to partaking of this curvilinear motion, the snow and vapor mixtures of the several streams or jets released into each one of the chambers 61 will be permitted to spread longitudinally of their chamber with the result that the several jets of mixture will merge to form a continuous mass equal in length to each chamber 61.

The curved surfaces of the rear chamber walls 62 will function to change the direction of motion of the released carbon dioxide snow and vapor. Because the carbon snow of the mixture is many times more dense than the carbon dioxide vapor, and because the velocity of both of these components is the same, the snow offers more resistance to the deflecting force provided by the rear, curved chamber walls. The snow, therefore, will force its way to the outer side of the curvilinear path of flow of the material with the result that it will displace the vapor or force it to seek a path of flow away from the interior surface of the chamber walls. The difference in density of the snow, as compared to the vapor, therefore, brings about a segregation of these two components; i. e., the snow will form a flowing layer in contact with the inner wall surface of each chamber while the vapor forms a superimposed layer that is spaced from the surface of the chamber wall.

The desired segregation of the snow and vapor is accomplished by the time the discharge reaches the open front of each one of the chambers 61. The snow layer for each chamber will be arranged adjacent the inner side wall 63 while the vapor layer will be arranged outwardly of the snow layer, or adjacent the discharge pipe 58 or 59. The final carbon dioxide discharge stream, therefore, will be formed by the segregated discharges from the two parallel chambers. The snow layers from the two chambers will lie adjacent to each other and immediately will merge. The vapor layers of the two discharges will be located out-

12

wardly of, or above and below, the merged snow layers and will sandwich the snow therebetween. It will be appreciated, therefore, that the final carbon dioxide discharge will consist of a core 5 that is formed by the two merged snow layers with the vapor layers shielding the snow core from the surrounding atmosphere. This final discharge stream will have a width which corresponds with the length of each chamber while 10 the depth or thickness of the final stream will be approximately equal to the distance between the adjacent sides of the discharge pipes 58 and 59.

Each one of the foam generating and discharging guns H of the apparatus shown in Figs. 3 to 6 15 inclusive will function in the same manner as the foam guns B of the apparatus shown in Figs. 1 and 2. Therefore, the description of the foam guns H will be presented as briefly as possible and will serve the purpose of only specifically describing the differences in structural design.

Each one of these foam generating and discharging guns is provided with a supply pipe line 67 that delivers a mixture of water and a foam stabilizing agent to the coupling or discharge manifold 68. This coupling or manifold of each gun is of elongated formation in longitudinal section. It is hollowed out, or chambered, so as to uniformly deliver the mixture of water and stabilizer to the longitudinally aligned series of 25 orifice jets 69. These jets function to deliver the mixture into the foam generating chamber 70 of each gun. A suitable strainer 71 is provided at the entrance or inlet for each coupling or discharge manifold 68 to separate out solid particles 30 or foreign matter that might clog up the jets 69.

The foam generating chambers 70 of the two guns H are formed in the members 71 which are so shaped as to provide pick-up spouts 72. These pick-up spouts are provided with inlet throats 40 73 that are arranged to receive carbon dioxide vapor from their respective segregating chambers 61.

This picked-up carbon dioxide vapor is delivered to the foam generating chamber 70 of each 45 member 71 and is so mixed with the water and foam stabilizing agent solution that the resultant foam has the carbon dioxide vapor entrapped in its bubbles. This generated foam is discharged to the delivering and directing tubes 74. By inspecting the several figures, it will be seen that these tubes 74 are of elongated shape in transverse section or are provided with major and minor cross sectional dimensions.

As was noted in connection with the fire extinguishing apparatus of Figs. 1 and 2, the foam guns H of the apparatus shown in Figs. 3 to 6 inclusive will function to produce ordinary mechanical air foam when the carbon dioxide nozzle G is not operating. That is to say, the pick-up spouts 72 will have air from the surrounding atmosphere drawn therein by the aspirating action produced by the discharges of water and a foam stabilizing agent delivered by the orifice tips 69.

It is to be understood that I do not desire to be limited to the exact order of method steps as they have been disclosed, for variations and modifications of the same, which fall within the scope of the accompanying claims, are contemplated. It further is to be understood that the particular types of apparatus herein shown and described are to be taken as preferred examples of the invention, and that various changes in the shape, size, and arrangement of parts may be resorted

to without departing from the spirit of the invention or the scope of the subjoined claims.

Having thus described the invention, I claim:

1. A method of discharging a fire extinguishing medium, comprising effecting sudden release of liquid carbon dioxide to lower its temperature sufficiently to form a discharge stream of snow and vapor, separately generating foam by mixing carbon dioxide diverted from the aforesaid discharge stream with a mixture of water and a foam stabilizing agent flowing under pressure, and projecting the generated foam as a stream in such an associated relation with respect to the carbon dioxide stream that the carbon dioxide and foam will be simultaneously applied to the same general area of a fire.

2. A method of discharging a fire extinguishing medium, comprising effecting sudden release of liquid carbon dioxide to lower its temperature sufficiently to form a mixture of snow and vapor, separating the snow and vapor components from each other and forming them into a composite discharge stream, separately generating foam by mixing carbon dioxide vapor diverted from the aforesaid composite discharge stream with a mixture of water and a foam stabilizing agent flowing under pressure, and projecting the generated foam as a stream in such an associated relation with respect to the carbon dioxide stream that the carbon dioxide and foam will be simultaneously applied to the same general area of a fire.

3. A method of discharging a fire extinguishing medium, comprising effecting sudden release of liquid carbon dioxide to lower its temperature sufficiently to form a mixture of snow and vapor, separating the snow and vapor components from each other and forming them into a composite discharge stream with the vapor shielding the snow from the surrounding atmosphere, separately generating foam by mixing carbon dioxide vapor diverted from the vapor shielding portion of the aforesaid composite stream with a mixture of water and a foam stabilizing agent flowing under pressure, and projecting the generated foam as a stream in such an associated relation with respect to the carbon dioxide stream that the carbon dioxide and foam will be simultaneously applied to the same general area of a fire.

4. A method of discharging a fire extinguishing medium, comprising discharging carbon dioxide snow and vapor into the atmosphere in the form of a stream, completely generating foam at a location removed from the stream of carbon dioxide by mixing water, a foam stabilizing agent and carbon dioxide diverted from the aforesaid stream to said foam generating location, and projecting the generated foam as a stream paralleling and flowing in the same direction as the carbon dioxide stream.

5. Fire extinguishing apparatus, comprising means for producing and discharging a stream of carbon dioxide snow and vapor, a foam generating chamber, means for delivering to said chamber a mixture of water and a foam stabilizing agent, means for delivering to said chamber carbon dioxide withdrawn from the carbon dioxide stream, and means for discharging and directing the generated foam from said chamber as a stream flowing in the same general direction as the carbon dioxide stream.

6. Fire extinguishing apparatus, comprising means for producing and discharging a stream of carbon dioxide snow and vapor, a foam generating chamber closely adjacent the aforesaid means, means for delivering to said chamber a mixture of water and a foam stabilizing agent, means for delivering carbon dioxide vapor to said chamber for entrapment in the bubbles of the foam, and means for discharging the generated foam from said chamber as a stream flowing in the same general direction as the carbon dioxide stream.

7. Fire extinguishing apparatus, comprising means for producing and discharging a stream of carbon dioxide snow and vapor, means for diverting carbon dioxide vapor from said stream, and means for producing and discharging in close proximity to the carbon dioxide stream a foam stream having entrapped in its bubbles the carbon dioxide vapor diverted from the carbon dioxide stream.

8. A method of extinguishing a fire, comprising the steps of first applying to the fire area a combined discharge of carbon dioxide and a foam which is completely generated, at a location removed from the discharged carbon dioxide, by mixing a foam stabilizing agent and carbon dioxide diverted from the aforesaid discharge, and, after the fire has been subdued sufficiently to permit the foam bubbles to remain intact, then applying to the fire area a discharge of foam having air from the surrounding atmosphere entrapped in its bubbles.
